US00D794024S

(12) **United States Design Patent** (10) **Patent No.:** **US D794,024 S**
(45) **Date of Patent:** **** Aug. 8, 2017**

(54) **DIRECTIONAL PAD FOR A CONTROLLER**

(71) Applicant: **Microsoft Corporation**, Redmond, WA (US)

(72) Inventors: **Christopher Kujawski**, Seattle, WA (US); **Kenneth Jasinski**, Bellevue, WA (US)

(73) Assignee: **Microsoft Corporation**, Redmond, WA (US)

(**) Term: **15 Years**

(21) Appl. No.: **29/543,897**

(22) Filed: **Oct. 29, 2015**

(51) LOC (10) Cl. **14-03**

(52) U.S. Cl.

USPC **D14/401**

(58) **Field of Classification Search**

(57) **CLAIM**

The ornamental design for a directional pad for a controller, as shown and described.

DESCRIPTION

FIG. 1 is a front perspective view of a directional pad for a controller showing our new design;

FIG. 2 is a top view thereof;

FIG. 3 is a bottom view thereof;

FIG. 4 is a rear view thereof;

FIG. 5 is a front view thereof;

FIG. 6 is a left side view thereof;

FIG. 7 is a right side view thereof;

FIG. 8 is a front perspective view of the directional pad for a controller of FIGS. 1-7 shown in an unclaimed controller environment;

FIG. 9 is a top view thereof;

FIG. 10 is a rear view thereof;

FIG. 11 is a front view thereof;

FIG. 12 is a left side view thereof; and,

FIG. 13 is a right side view thereof.

The broken line showing of the various unshaded elements of the directional pad for a controller in FIGS. 1-13 is for environmental purposes only and forms no part of the claimed design.

1 Claim, 10 Drawing Sheets

US D794,024 S
